UNITED STATES PATENT OFFICE.

SCHUYLER HAZARD, OF CINCINNATI, OHIO.

DESIGN FOR A RAILWAY-RAIL.

SPECIFICATION forming part of Design No. 32,406, dated March 27, 1900.

Application filed July 27, 1899. Serial No. 725,328. Term of patent 14 years.

To all whom it may concern:

Be it known that I, SCHUYLER HAZARD, a citizen of the United States, residing at Cincinnati, county of Hamilton, State of Ohio, have invented and produced a new and useful Design for a Railway-Rail, of which the following, taken in connection with the accompanying drawings, is a full and exact description.

Figure 1 is a perspective view of a portion of a railway-rail embodying my design, and Fig. 2 is a transverse section of said railway-rail shown in Fig. 1.

The form or configuration embodying my design comprises the base-flanges *a a*, united with the vertical web *b*, terminating above in the head *c*, which has a plain upper surface or wheel-tread *c'*, the vertical side of the web *b* (marked 1) being shorter than its opposite side (marked 2) and the head *c* being of

greater depth on one side of the web, as at 3, than it is on the other side, (marked 4,) the head on the side marked 3 also projecting farther from the central line of the web *b* than does the opposite side, (marked 4.)

The leading and material features of the design are the unequal sides of the vertical web (marked *b*) taken in conjunction with the unequal lateral projection or eccentricity of the head, (marked *c*.)

What I claim is—

The design for a railway-rail herein shown and described.

In testimony whereof I have hereunto affixed my signature this 25th day of July, 1899.

35

SCHUYLER HAZARD.
